(57) CLAIM

The ornamental design for a foldable baby playpen as shown and described.

DESCRIPTION

FIG. 1 is a front elevational view of a foldable baby playpen showing the new design in a semi-folded position;

FIG. 2 is a rear elevational view thereof;

FIG. 3 is a left-side elevational view thereof;

FIG. 4 is a right-side elevational view thereof;

FIG. 5 is a top plan view thereof;

FIG. 6 is a bottom plan view thereof;

FIG. 7 is a perspective view thereof;

FIG. 8 is an enlarged view of the encircled portion '8' in FIG. 1 thereof;

FIG. 9 is an enlarged view of the encircled portion '9' in FIG. 1 thereof;

FIG. 10 is an enlarged view of the encircled portion '10' in FIG. 2 thereof;

FIG. 11 is an enlarged view of the encircled portion '11' in FIG. 4 thereof;

FIG. 12 is an enlarged view of the encircled portion '12' in FIG. 5 thereof;

FIG. 13 is an enlarged view of the encircled portion '13' in FIG. 6 thereof;

FIG. 14 is an enlarged view of the encircled portion '14' in FIG. 6 thereof;

FIG. 15 is a front elevational view of a foldable baby playpen showing the new design in a closed position;

FIG. 16 is a rear elevational view thereof;

FIG. 17 is a left-side elevational view thereof;

FIG. 18 is a right-side elevational view thereof;

FIG. 19 is a top plan view thereof;
 FIG. 20 is a bottom plan view thereof;
 FIG. 21 is a perspective view thereof;
 FIG. 22 is an enlarged view of the encircled portion '22' in FIG. 17 thereof;
 FIG. 23 is a perspective view of a foldable baby playpen showing the new design in an open state; and,
 FIG. 24 is another perspective view thereof.
 The broken lines shown in the drawings are for the purpose of illustrating portions of the article and form no part of the claimed design.
 The long-short-short-long broken line circles in FIGS. 1, 2, 4-6, 8-14, 17, and 22 depict the limits of the enlarged views and form no part of the claimed design.

1 Claim, 24 Drawing Sheets
